UNITED STATES PATENT OFFICE.

CHARLES FARMER, OF NOTTINGHAM, ENGLAND.

MULTIPLE EMBROIDERING-MACHINE.

No. 831,046.

Specification of Letters Patent.

Patented Sept. 18, 1906

Application filed September 29, 1904. Serial No. 226,541.

To all whom it may concern:

Be it known that I, CHARLES FARMER, a subject of the King of Great Britain, and a resident of Nottingham, England, have invented certain new and useful Improvements in or Relating to Multiple Embroidering-Machines, of which the following is a specification.

This invention relates to multiple-shuttle embroidery-machines, and refers more particularly to improved means for putting a certain proportion of the needles out of action and bringing them into action again as required or for changing the needles in action for others which have been put out of action, according to the nature and requirements of the work in hand.

It also refers to an improved needle-thread-tension device which will permit of the above changes being made.

Referring to the drawings, Figure 1 is a plan, and Fig. 2 a sectional side elevation, showing needle operating and thread-tension mechanism of an embroidery-machine constructed according to my invention. Fig. 3 is a front elevation showing the means for longitudinally adjusting the needle-driving bar. Fig. 4 is a view showing the cam for actuating the needles. Fig. 5 is a front elevation showing the mechanism for controlling the needle-thread-tension device. Fig. 6 is a side elevation, and Fig. 7 a sectional elevation, of the driving-bar.

Like letters indicate like parts throughout the drawings.

According to this invention each needle A (see Figs. 1 and 2) is carried by an independent needle-bar A', and the latter are carried in front and back bearings formed in fixed longitudinal bearing-bars B, carried by brackets secured to the front rail C of the machine. The needle-bars A' are situated at right angles to the embroidery-frame (which is not shown) and are moved longitudinally in their bearings to and from the said frame by the following arrangement:

Preferably at a point between the bearing-bars B described each needle-bar A' is provided on its under side with two transverse openings A² A³ (see Fig. 2) and the upper edge of what may be termed a "longitudinal driving-bar" D normally engages in the opening A² of each needle-bar and actuates the whole of them. This longitudinal driving-bar D is connected to the plungers D², which are ordinarily used for carrying and

reciprocating a longitudinal needle-bar in machines of ordinary construction, and the driving-bar D is thus reciprocated in the same manner, and by reason of its upper edge 60 engaging in the transverse openings A² of the needle-bars A' the requisite movement is imparted to the latter. The driving-bar D is not directly attached to the plungers D², but is mounted in guideways D', formed in brackets D³, secured to said plungers, and these guideways are disposed, as shown, so that the driving-bar D can be moved longitudinally. The upper edge of the driving-bar D is also at certain points cut away, leaving gaps or 70 openings D⁴, (see Fig. 6,) and when by a longitudinal movement of the bar D certain of these gaps D⁴ are caused to register with certain of the needle-bars A' the latter are disconnected from the bar D and remain stationary. The upper edge of the driving-bar D may, for example, be cut in the same manner as that shown in Fig. 6, which is set out according to the following system:

A space equal to one-fourth of the distance between the needles is taken as the unit of the longitudinal movement of the driving-bar D, while the gaps D⁴ in said bar and the space between them are also equal in length to either one, two, three, or more of these 80 units and are so disposed as to give the following result: When the driving-bar D is in its normal position, as shown in Figs. 1 and 6, it engages with the whole of the needle-bars A', and if it be moved to the left four or 90 eight units it will in each case again engage the whole of the needle-bars A'.

If the bar D is, however, moved to the left one or five units, it will engage every other needle-bar only; but in the first case it will engage the 95 odd-numbered ones and in the second case the even-numbered ones. If the bar D is moved two, six, or ten units to the left, it will engage every third needle-bar but in each case the needle-bars engaged will be 100 different. If the bar D is moved three, seven, or eleven units to the left, it will only engage every fourth needle-bar, and in this case the bars engaged will be different for each of the different distances it is moved.

It will thus be seen that with the system employed any change in the needles likely to be required may be obtained by the longitudinal movement of the driving-bar D. The left-hand end only of the driving-bar D is shown; but it will be understood that the remainder of the bar is cut so as to form a series of re-

peats of the part shown, the repeat occurring every twelve needle-bars.

In addition to the reciprocating driving-bar D described, a locking-bar E (see Figs. 1 and 2) of similar construction to the driving-bar D, but not capable of reciprocating with the said bar D, is employed to lock and hold those needle-bars A' which are for the time being disengaged from the driving-bar D and are thus put out of action. This locking-bar E is situated at the back of the driving-bar D and is carried in fixed guideways E', formed in the back bearing-bar B, previously described, so that it can be moved longitudinally when desired. This locking-bar E is adapted to engage in the second opening A³ in each of the needle-bars A', and its upper edge is cut or provided with gaps E⁴, disposed inversely to those in the driving-bar D, as shown, so that when it is moved longitudinally the same distance as the driving-bar D it engages in the opening A³ of and holds those needle-bars A' which are disconnected from the driving-bar D.

The two bars D and E described may be connected together and both be moved longitudinally by a screw or other convenient arrangement in connection with one of them, provided such connection allows of the requisite independent reciprocation of the bar D, or, as shown, the driving-bar D may be normally disconnected from the bar E and be only connected to it at the time a change is to be made, so that both are moved the requisite distance at one operation. In this case the needle-cam—that is, the box-cam F (shown in Fig. 4)—used for operating the driving-bar D is cut away or formed with a depression at F', so that after the needles have been withdrawn by the action of this cam to the usual extent required in ordinary working the driving-bar D may, together with the needle-bars A', be withdrawn or moved rearward a farther short distance, the antifriction-roller used in connection with the cam entering the depression at F' in the cam F and permitting of this movement. This movement brings the driving-bar D close up to the locking-bar E, and pins or studs D⁵ (see Fig. 1) on the back of the former then enter corresponding openings E² in the locking-bar E and for the time being locks the two bars together. The same movement also causes the openings A³ in the needle-bars A' to register with the locking-bar E. Any desired change in the needles in operation may now be made by moving both bars longitudinally, as previously described, when the driving-bar D may be returned to its normal or working position again, together with those needle-bars A' which are still connected to it, while those needle-bars A' which are disconnected will be held by the locking-bar E in the same position in which the change was effected.

In order to conveniently move the bars D and E longitudinally, as described, the end of the locking-bar E is provided with a toothed rack E³, (shown more clearly in Fig. 3,) which engages with a pinion G, mounted on a shaft G', which latter is carried in bearing-brackets G², secured to the rail C at one end of the machine. This shaft G' is provided with a hand-wheel G³, by means of which the operator can rotate the said pinion G, and thus move the bar E, together with the bar D, when it is connected to E, longitudinally in either direction.

The inner bearing-bracket G² is provided with a part G⁴, which forms a guide for the end of the toothed rack E³, and said part may be provided with a hole and the rack E³ with a series of holes the requisite distance apart, so that a pin G⁵ may be inserted in the hole in the part G⁴ and one of those in the rack E³ when the latter has been moved the required distance. This assists the operator in longitudinally adjusting the bars D and E, as it acts as an index and also prevents accidental displacement.

The hereinbefore-described rearward movement of the driving-bar D and needle-bars A' may be utilized to trap and hold the needle-threads of those needles which are put out of action and prevent them from being withdrawn from the eyes of the needles. For this purpose each needle-thread may be carried under the inner end of a spring A⁴, (see Figs. 1 and 2,) secured to the corresponding needle-bar A', and when moved rearward, as described, the needle-threads A are each trapped under the end of this spring A⁴ and the top of the front bearing-bar B and are thus in each case held by said spring until the needle-bar is returned to its normal or working position again. With the arrangement described the needles in operation may be expeditiously changed from time to time as the work proceeds, while the two bars D and E may be cut or the gaps D⁴ distributed so as to give any change or series of changes in the needles in operation which may be required for the particular class of work in hand. As certain of the needles are at times out of operation it is obvious that a common tension-roller over which the whole of the needle-threads are carried is in this case inapplicable. In order to obviate this difficulty, independent needle-thread-locking devices are provided in connection with each needle in conjunction with a bar common to all the threads to draw the thread off the cops, as required. The several parts of this thread-tension are preferably arranged as follows:

In connection with each needle-thread a there is a fixed bracket or abutment H, (see Figs. 1, 2, and 3,) the whole of which are secured in a straight line on a bar H', carried by the bearing-brackets H² on the rail C. Carried through openings in these abutments H

is a longitudinal bar J. On the left of each abutment H is a pair of thread-locking disks H³, and on the right is a second pair H⁴, each of which is normally held up to its abutment by, say, a spiral spring H⁵, situated between the said disks and an intermediate arm J', secured on the bar J. The locking-disks H³ and springs H⁵ are mounted on short pins H⁶, (see Fig. 2,) which are dropped in between the abutments H, the sides of the latter being recessed to receive the ends of the same. The springs H⁵ are adjusted so as to put a slight pressure on both sets of locking-disks H³ H⁴ when the arms J' are in their intermediate positions, as shown, while the bar J is reciprocated longitudinally by a cam and suitable connections, so as to move the arms J' toward one or the other of the abutments H on either side of them, so as to put a heavy pressure first on the disks H³ on the left of the abutments H and then on those, H⁴, on the right alternately, while, on the contrary, the pressure is altogether released on the reverse side to which the heavy pressure is applied. Each needle-thread a is carried from its cop T (see Figs. 1 and 2) to the pair of locking-disks H³ on, say, the left of the abutment H, (shown more clearly in Fig. 1,) then over a thread-bar K common to all the threads carried by arms K' on a rocking shaft K², and from this point back to the pair of locking-disks H⁴ on the right of said abutment and from thence to the ordinary vibratory feed-bar L of the machine. It therefore follows that by the longitudinal reciprocating movement of the bar J the thread a is first locked by one pair of locking-disks H³ at a point where the thread is feeding up to the thread-bar K and then by the other pair H⁴ at a point where the thread is feeding away from the said bar K, while it is released altogether at one of the said points when it is locked at the other. For instance, when the vibratory feed-bar L of the machine is moved to draw off the thread for the next stitch each thread a is released by the pair of disks H⁴—that is, at a point between the thread-bar K and feed-bar L—while they are locked by the disks H³ between the cop T and thread-bar K, so that the act of drawing off the thread draws in the thread-bar K. The thread-bar K is normally free with the exception of weight or brake mechanism which may be adjustable so as to regulate the tension on the threads, and it is drawn inward, as described, against the action of said weight or brake.

When the stitch is being made, each thread a is locked by the disks H⁴ and released by the disks H³—that is, now locked between the thread-bar K and feed-bar L and released between the thread-bar K and cop T—and the said bar K is at this time positively returned to its normal position again, so as to draw the same amount of thread off each cop T as that taken by the

feed-bar L. As the action of the feed-bar L will only draw off the needle-threads a of those needles which are for the time being in action, it follows that the thread-bar K when returned to its normal position will 7c only act on the corresponding threads and draw a fresh supply of the same from the cops T, while the threads of those needles which are not in operation will be unaffected. The needle-threads a can therefore be drawn 75 off by those needles in use without any assistance from or in any way interfering with the threads of those needles which are inoperative and the changing of the needles in operation may thus be made from time to 80 time without reference to the needle-thread-tension mechanism. The threads a are locked by the disks H⁴ until the stitch is completed and are therefore securely held at this point against the action of the vibrating 85 tension-bar N of the machine when the latter is moved to draw up and tighten the stitch.

The characteristic feature of the arrangement described is that the thread-tension is separate and distinct for every needle, so that one is entirely independent of the other. At the same time only one bar common to all the threads is required to let off the threads to form the loops and subsequently draw up the stitches in the fabric, while a 95 second bar draws the threads from the cops and regulates the tension on the whole of the threads. The thread-bar K is positively returned to its normal position again, as previously described, by the following mechanism: The rocking shaft K², which carries the thread-bar K and is provided with a weighted arm or brake mechanism of any well-known construction adapted to regulate the power required to move it angularly, is actuated by means of a cam O (see Fig. 5) on the main driving-shaft P at the end of the machine. The cam O actuates, through the intermediary of a lever O', a tappet-rod O², which is carried through openings in the free ends of arms K' on a rocking shaft K², and is provided with tappets O³ to engage said arms and return the bar K to its normal position again after it has been drawn in by the needle-threads. 110 115

The bar J of the tension mechanism is reciprocated longitudinally, as hereinbefore described, by means of a cam R on the shaft P, through the intermediary of a cam-lever R', link R², and bell-crank lever R³, engaging 120 the bar J of the lower tier of needles, as shown. That of the upper tier is actuated by a second link S, connected to the cam-lever R', and an arm S', link S², and bell-crank lever S³. The bell-crank levers R³ and S³ are 125 pivoted to brackets R⁴ and S⁴, respectively, which also serve to support the ends of the bars J, and the bell-crank levers R³ S³ are provided with forked ends to engage with collars R⁵ S⁵ on the respective bars J. Other 130

means may, however, in some cases be found more convenient for actuating the bars J.

In the process of embroidering it is necessary at times to draw off a certain amount of needle-thread when the machine is standing, in order that the embroidering-frame may be moved some distance to bring a new part of the fabric opposite the needles. For this purpose provision may be made for disconnecting either the bar J from the cam-lever R' or the latter from the cam R, so that the operator can move the bar J and thus release the threads at K³ or K⁴, as required, the thread-bar K being also at this time moved by the operator so as to draw off the cops again the amount of thread taken by the said movement of the embroidering-frame.

What I claim as my invention, and desire 20 to secure by Letters Patent, is—

1. In a multiple embroidering-machine, the combination of the needles, needle-bars to carry said needles, a driving-bar adapted to engage the whole or a portion of the needle-bars, means for actuating the driving-bar, two needle-thread-locking devices in connection with each needle, means for compressing and releasing said devices alternately, a thread-bar which can be drawn in by the 25 needle-threads, and means for returning the thread-bar to its normal position again, substantially as described.

2. In a multiple embroidering-machine, the combination of a series of needle-bars 35 each provided with a notch to admit the edge of the driving-bar, a driving-bar having its edge engaging in said openings and formed at intervals with gaps or recesses so disposed that the disengagement of different groups of 40 needle-bars may be effected by adjusting said bar longitudinally, means for actuating said driving-bar adapted to permit of its longitudinal adjustment, and means for effecting its longitudinal adjustment, substantially 45 as described.

3. In a multiple embroidering-machine, the combination of a series of needle-bars each provided with two notches, a driving-bar formed with gaps or recesses leaving 50 parts to engage in one of said notches in each of the needle-bars, a locking-bar formed with gaps or recesses leaving parts to engage in the other notch of each needle-bar, means for actuating the driving-bar arranged to permit of its longitudinal adjustment, and means for moving both bars longitudinally, substantially as described.

4. In a multiple embroidering-machine, the combination of the needles, means for reciprocating them, two needle-thread-locking devices for each needle-thread, means for compressing and releasing said devices alternately, a thread-bar over which the thread is carried on its way from one locking device 65 to the other and which can be drawn in by

the needle-threads, and means for returning the thread-bar to its normal position again after being drawn in, substantially as described.

5. In a multiple embroidering-machine, 70 the combination of the needles, means for reciprocating them, a thread-bar which can be drawn in by the needle-threads, means for positively returning said bar to its normal position again, two needle-thread-locking devices in connection with each thread so disposed as to hold each needle-thread at points where it is feeding up to and away from the said thread-bar, and means for compressing and releasing said devices alternately, substantially as described.

6. In a multiple embroidering-machine, the combination of the needles, means for reciprocating them, a thread-bar which can be drawn in by the needle-threads and is then 85 positively returned to its normal position again, means for returning the thread-bar to its normal position, two pairs of needle-thread-gripping disks to each needle one pair disposed to hold the needle-thread at a point 90 where it is feeding up to and the other at a point where it is feeding away from the thread-bar, and means for compressing one of each pair of said disks and releasing the other of each pair alternately; substantially 95 as described.

7. In a multiple embroidering-machine, the combination of the needles, means for reciprocating them, two needle-thread-gripping disks in connection with each needle situated on opposite sides of a fixed support, movable parts situated between the pairs of gripping-disks, springs between said parts and gripping-disks, means for carrying and reciprocating the movable parts, a thread-bar which 100 can be drawn in by the needle-threads co-operating with the said gripping-disks, and means for returning the thread-bar to its normal position again after being drawn in, substantially as described.

8. In a multiple-shuttle embroidering-machine the combination of the needles, means for reciprocating them, a series of abutments, pairs of needle-thread-gripping disks arranged on each side of said abutments, movable arms situated between said abutments controlling adjacent members of two separate pairs of disks with the exception of those at the ends of the series, springs between said arms and disks, means for carrying and operating said arms, a thread-bar which can be drawn in by the needle-threads co-operating with the thread-gripping disks, and means for returning said bar to its normal position again after being drawn in, substantially as 115 described.

9. In a multiple-shuttle embroidering-machine, the combination of the needles, means for reciprocating them, a series of abutments, pairs of locking-disks one on each side of each 120

abutment, a bar provided with intermediate arms, springs between said arms and locking-disks, means for reciprocating the bar longitudinally, a thread-bar round which each 5 thread is carried on its way from one pair of gripping-disks to the other, said bar being free so that it can be drawn in by the needle-threads at the proper time, and means for returning the thread-bar to its normal position 10 again after being drawn in, substantially as described.

10. In a multiple embroidering-machine the combination with the needle-bars, of springs adapted to coöperate with a fixed 15 part of the machine and trap the threads of those needles which are withdrawn from action, and means for permitting the needle-bars to be withdrawn beyond the normal point substantially as described.

20. 11. In a multiple embroidering-machine, the combination with the needle-bars, of bearing-bars for supporting them, springs on the needle-bars so disposed as to trap and hold the needle-thread between said spring 25 and one of the bearing-bars when the needle-bars are withdrawn out of action, and a depression in the needle-operating cam to permit of the needle-bars being withdrawn beyond the normal point, substantially as de- 30 scribed.

12. In a multiple embroidering-machine the combination of the needles, needle-bars

to carry said needles each provided with two notches, a driving-bar formed with gaps or recesses leaving parts to engage in one of said 35 notches in each of the needle-bars, a locking-bar formed with gaps or recesses leaving parts to engage in the other notches of those needle-bars which are disconnected from the driving-bar, means for actuating the driving-bar adapted to permit of its longitudinal adjustment, means for moving both bars longitudinally, two pairs of needle-thread-gripping disks in connection with each needle-thread, fixed abutments between each of the 45 two pairs of gripping-disks, movable arms between said abutments, springs between said disks and arms, a bar to carry said arms, means for reciprocating said bar, a thread-bar round which each thread is carried on its 50 way from one pair of gripping-disks to the other, said bar being free at the proper time so that it can be drawn in by the threads, and means for returning the thread-bar to its normal position again after being drawn in, sub- 55 stantially as described.

In testimony whereof I have signed my name to this specification in the presence of two subscribing witnesses.

CHARLES FARMER.
